This is a continuation-in-part of application Serial No. 586,948, filed April 6, 1945, now abandoned, and which application is entitled "Adjustable Cabinet Hinge".

This application relates to an improvement in semi-concealed combination adjustable hinge and cabinet supports.

UNITED STATES PATENT OFFICE

2,527,403

HINGE

Reese G. Davis and Murray C. Davis,
Forty Fort, Pa.

Application April 6, 1945, Serial No. 586,948

2 Claims. (Cl. 16—135)

1

Our invention relates to an improvement in semi-concealed combination adjustable hinge and cabinet supports.

An object of our invention is to provide a cabinet door hinge which will serve not only to hinge a door on a cabinet, but also to securely support the corner of the cabinet.

A further object is to provide a hinge secured to a corner of a cabinet, supporting the cabinet members securely in their adjusted position, and hinging thereto one corner of a door.

A still further object is to provide a cabinet hinge which may be secured to a corner of a cabinet, and which may support a cabinet door so that the door may be adjusted laterally of the cabinet without actually removing the door therefrom.

A still further object is to provide a cabinet door hinge which may be secured to the cabinet, and which may be utilized to secure the adjacent sides of two cabinets together.

In the accompanying drawings:

Fig. 1 is a perspective view of a hinge to support the upper left hand corner of a cabinet door;

Fig. 2 is a plan view of the same hinge;

Fig. 3 is a front elevation;

Fig. 4 is a side elevation;

Fig. 5 is a plan view of the portion of the hinge adapted to be secured to the door;

Fig. 6 is a plan view of the portion of the hinge adapted to be secured to the cabinet; and

Fig. 7 is a front elevation showing four of our hinges secured to four cabinet corners.

For ease of understanding, attention will be directed first to Fig. 7, wherein four adjacent cabinet corners are shown, and to which four hinges have been properly attached so that their respective doors may be properly hung on the hinges to serve as closures for the individual cabinets. Such door closures may be hung on our hinges in such manner that the edges of the doors may be practically contiguous with the next adjacent doors. In the upper right-hand corner of Fig. 7, we have disclosed a cabinet having a vertical side wall or jamb 2, and a horizontal portion or base 4, which in accordance with conventional construction are joined together at right-angles. In the upper left corner of Fig. 7, a vertical side or jamb 6 is shown at approximate right-angles to the base or horizontal section 8 of a cabinet corner positioned contiguous to the first cabinet corner described above. Directly beneath the cabinet corner in the upper right-hand corner of Fig. 7, the vertical wall or jamb 10 is shown with its top or horizontal frame member 12 positioned at

right-angles to one another. In the lower left hand corner, the same structure obtains, there being a vertical side wall or jamb 14 positioned at right-angles to the horizontal frame member or top 16.

It will be obvious that the hinges disclosed in Fig. 7, and about to be described, on the upper right-hand side and the lower left hand side, as well as hinges on the upper left hand side and the lower right hand side, are identical.

Preferably, we make our hinges of pressed metal or the like, which have been made and proven satisfactory in sixteen gauge, although it will be understood that either a heavier or a lighter gauge can be used in the event that heavier or lighter doors are to be attached to cabinets. The main body portion 20 of the hinge is adapted to be secured to a door jamb, such as the door jambs 2, 6, 10 and 14, by suitable screws 22 being driven through the body portion 20 and into the door jamb members. The main body portion 20 of the hinge also is preferably provided with an outstanding ear 24, which is provided with a suitable hole through which a conventional screw 26 may be driven into the horizontal member 4, 8, 12, or 16 of the cabinet which is adapted to be positioned at right-angles to the vertical sections or jambs of the cabinet. In this manner, the main body portion 20 of the hinge forms in effect an angle-iron securely to maintain the right-angle sides of a cabinet.

The main body portion of the hinge is also provided with an extended portion, which is bent over at right-angles to the main body portion to form a plate 28, through which a suitable hole is drilled, so that a screw 30 may be driven into the side member of door jamb 2, 6, 10 or 14. Screw 30 will obviously be at right-angles to the screws 22, and will position the main body 20 of the hinge securely on the cabinet frame or door jamb. The plate 28 is also preferably provided with an aperture 32 so that a suitable bolt 34 may be utilized to additionally secure two hinge body portions together on their respective vertical side portions or jambs (for example 2 and 6) and at the same time serve to hold the two contiguous cabinets securely together.

One end of the main body portion 20 of the hinge is bent over at an approximate right-angle to form the support or wing 36, which is to be pivotally secured to the portion of the hinge fastened to the door to be hung. The flat portion 40 of the hinge which is adapted to be secured to a door to be hung is preferably made of pressed metal or the like, and this flat portion 40 of the

hinge may also be made of any suitable gauge, depending upon the size and weight of the door which must be hung.

The flat portion 40 of the hinge is adapted to be pivotally secured to the support or wing 36 by means of a suitable rivet 42 which will be upset at its ends so that it will not become disengaged from the holes provided in the support 36 and the door portion 40 of the hinge. These two portions of the hinge preferably do not directly contact one another but are separated by the insertion of a suitable washer 44 positioned therebetween.

The flat portion 40 of the hinge, which is adapted to be secured to the door to be hung, has a portion thereof bent over at right-angles to the main portion. The portion 40, as clearly shown in figures, may be provided with one or more oblong apertures 46, through which suitable screws may be driven into a door which is to be hung. The portion 50, which is bent at right-angles to the main flat portion 40 of the hinge, is likewise provided with an oblong aperture 52, through which a suitable screw may be driven into the door.

It will be understood that screws driven through the oblong apertures 46 and 52 will be approximately at right-angles to one another, and consequently will securely hold the door on the door portions 40 and 50 of the hinge. These apertures are preferably made in an elongated form, so that a door which has been hung may be conveniently moved either toward or away from the axis of pivoting the hinge by merely loosening the screws and subsequently tightening them after the door has been placed in its re-adjusted position.

It will be understood that by the use of our hinge, four separate and distinct corners of four separate cabinet spaces may be securely positioned contiguously, as shown in Fig. 7, and to these corners proper doors may be conveniently hung and may be adjusted so that their adjacent edges may be made to be practically contiguous. Also, while we have shown in the drawings only four contiguous and adjacent corners, it will be understood that hinges identical with those shown in Fig. 7 will be utilized in hinging the conventional cabinet doors. For example, as is customary, one hinge will be secured to a bottom corner of a given cabinet door, and one hinge will also be secured to the top corner of the same door on the same door edge.

By this construction of hinge it will be seen that cabinet doors, or the like, may be hung so that doors mounted on the same horizontal tier may be positioned to have their pivoted edges practically contiguous, and doors of the tier below (or above) may be positioned to be very closely adjacent.

We claim:

1. In a hinge comprising a leaf member having an outwardly extending horizontal flat wing portion, a vertically disposed flange extending at right-angles to the said wing portion, a second flange extending inwardly and upwardly from the lower portion of the said first mentioned flange and terminating at a point intermediate its ends, and a projection disposed between the upper ends of the said first and second flanges, the said projection and the said second flange being disposed on the same side of the first flange.
2. A hinge comprising a leaf member having an outwardly extending horizontal flat wing portion, a vertically disposed flange extending at right-angles to the said wing portion, a second flange extending inwardly and upwardly from the lower portion of the said first mentioned flange and terminating at a point intermediate its ends, a projection disposed between the upper ends of the said first and second flanges, the said projection and said second flange being disposed on the same side of the said first flange, and a door leaf comprising a horizontally disposed flat portion, a vertical flange extending from the inner side of said horizontal flat portion, and a pivot connecting the outer ends of the said wing and said horizontal flat portion.
